DESIGN FOR A SPRAYER FOR LAUNDRIES OR THE LIKE

Wallace B. Roland, Oakland, Calif.

Application November 14, 1947, Serial No. 142,534

Term of patent 3½ years

(Cl. D62—2)

To all whom it may concern:

Be it known that I, Wallace B. Roland, a citizen of the United States, residing at Oakland, in the county of Alameda and State of California, have invented a new, original, and ornamental Design for a Sprayer for Laundries or the like, of which the following is a specification, reference being had to the accompanying drawing, forming part thereof.

Figure 1 is a perspective view of a sprayer for laundries or the like, embodying my new design.

Fig. 3 is a side elevation thereof, and

I claim:

The ornamental design for a sprayer for laundries or the like, substantially as shown.

WALLACE B. ROLAND.
